UNITED STATES PATENT OFFICE.

NORMAN VINCENT DYTE, OF HIGHGATE, LONDON, ENGLAND.

TROUSERS AND LIKE PRESS.

1,394,290.

Specification of Letters Patent. Patented Oct. 18, 1921.

Application filed June 16, 1920. Serial No. 389,365.

To all whom it may concern:

Be it known that I, NORMAN VINCENT DYTE, a subject of the King of Great Britain, residing at Highgate, London, England, have invented certain new and useful Improvements in Trousers and like Presses, of which the following is a specification.

The object of this invention is to construct a press for trousers or other wearing apparel in a simple and cheap manner and whereby an efficient pressing of the trousers, ties or other garments is obtained.

My invention will be clearly understood from the following description aided by the annexed drawings in which—

Figure 1 is a perspective view of a trousers press constructed according to my invention, and

Fig. 2 a part perspective view of a modified construction.

For the purpose of my invention I construct the press from two boards as is usual, one board A being preferably continuous or integral and the other B consisting of two boards connected together and in spaced relation to allow for non-pressing of the seams of trousers legs, but for pressing ties I prefer both boards A, B to be continuous or integral.

To the bottom board A and across same I affix two or more bars or plates C, C, the free ends of which extend beyond the side edges of the board. The ends of the bars or plates C, C are turned at right angles to the board and extend above said board as at D, D such extensions D, D being provided with inclined slots E, E hooks or equivalent.

To the other or upper board B and across same I affix two or more bars or plates F, F, corresponding to the bars or plates C, C, on the bottom board A, and of such a length that they will when the top and bottom boards are assembled, lie just within the right angled extensions D, D of the bottom bars C, C, and extension pieces G, G are formed on the bars or plates F, F, which will extend past the right angled extensions D, D, these extension pieces G, G being on the inside of the bars F, F so that the top and bottom boards when assembled cannot be moved laterally or longitudinally of one another, but can only be moved toward and away from one another.

Each of the bars or plates F, F on the top of board B carries a spring H. Preferably, and as shown in Fig. 1, these springs are

each formed of a length of tempered wire of round or other suitable cross-section secured midway of its length to the bar or plate F at a point approximately half way between the ends of the latter and provided between its point of attachment to the bar or plate F and each of its ends with a coil J, the coils being so arranged that they will engage or lie near the plates F and the board B when in normal position. The free end of each of the springs H extends beyond the side edges of the boards and is provided with a handle K.

In place of one spring on each bar or plate I may employ two springs H as in Fig. 2, in which case the inner ends will be secured to the plates F.

In use the boards are separated and the garments placed on the bottom board A and the top board B placed in position, as is usual, and to clamp them together, the free ends of the springs H are pressed down and engaged in the inclined slots E, or equivalents, in the right angled extensions D of the bottom board plates C and the coil or coils J, J of the springs H will exert the maximum pressure on the top member B near the side edges of the latter and on the fold or crease of the trousers where the pressing is most needed.

The right angled extensions D are preferably provided with a series of inclined slots E, or equivalents, so that the springs H can engage one or the other according to the thickness of the articles being pressed. The extensions G of the plates or bars F each engage one edge of one of the right angled extensions D so as to prevent relative longitudinal movement of the boards A and B.

It will be understood that for pressing ties the press is preferably constructed with an integral top board made smaller or narrower than for pressing trousers.

What I do claim as my invention and desire to secure by Letters Patent, is:—

1. An apparatus of the class described comprising top and bottom pressing boards bodily movable toward and away from one another, a plurality of guide standards extending vertically above the bottom board at opposite sides thereof and forming retaining guides for the top board, and spring means carried by the top board and engageable with said vertical standards.

2. An apparatus of the class described, comprising top and bottom pressing boards

bodily movable toward and away from one another, a plurality of guide standards extending above the bottom board at opposite sides thereof, spring members carried by the top board engageable with said standards, and means carried by the top board associated with said standards to prevent relative longitudinal movement of said boards.

3. An apparatus of the class described, comprising a bottom board having a plurality of vertical guide standards at each side thereof, a top board comprising two

parts longitudinally spaced apart disposed between said standards and movable bodily toward or away from the bottom board and 15 spring means carried by the top board and engageable with said standards.

In testimony whereof I have hereunto set my hand in presence of two subscribing witnesses.

NORMAN VINCENT DYTE.

Witnesses:
